SPINNER

Edward B. Benson, Kansas City, Mo., assignor to
 The Benson Manufacturing Company, Kansas
 City, Mo., a corporation of Missouri

Application December 30, 1940, Serial No. 372,224

6 Claims. (Cl. 170—159)

My invention relates to a spinner and more particularly to a spinner construction for use with the head of a variable pitch airplane propeller.

The housing for the variable pitch mechanism of a controllable pitch airplane propeller is built for utility and not for stream-lined shape. It has been necessary, in the interests of the principles of aerodynamics, to cover the head portion of the propeller with a spinner cone faired into the sheathing and properly stream-lined. The problem of mounting the spinner in a manner to give quick and facile access to all of the parts of the head for the purpose of adjusting the pitch of the propeller or the mechanism controlling the pitch, has been a difficult one. Heretofore, the methods of attaching the spinners have been such that considerable time has been consumed in removing and replacing them.

One object of my invention is to provide a simple, one-piece spinner which may be quickly and easily attached and detached from its position covering the variable pitch propeller mechanism.

Another object of my invention is to provide a spinner which is symmetrical in shape, light in weight, and which may be accurately positioned upon the propeller hub to protect the propeller hub mechanism and to stream-line the same.

Other and further objects of my invention will appear from the following description.

In the accompanying drawings which form part of the instant specification and are to be read in conjunction therewith and in which like reference numerals are used to indicate like parts in the various views;

Figure 1 is a sectional elevation showing one embodiment of my invention.

Figure 2 is a sectional view, taken on the line 2—2 of Figure 1.

Figure 3 is a fragmentary sectional view, taken on the line 3—3 of Figure 1.

Figure 4 is a fragmentary sectional view, on an enlarged scale, taken along the line 4—4 of Figure 3.

Figure 5 is a fragmentary sectional view on an enlarged scale, taken along the line 5—5 of Figure 2.

Figure 6 is a fragmentary sectional view, on an enlarged scale, taken along the line 6—6 of Figure 2, showing the locking means.

The propeller hub proper 1, is secured to the crank shaft of the engine, the crank case 2 of which appears in the drawings. Controllable pitch mechanism is mounted in a housing 3. The

propeller hub carries propeller blades 4. A diaphragm 5 is secured to the hub by means of bolts 6. Another diaphragm 7 is secured to the hub by means of bolts 8 and a hub flange 16. The bolts 8 also secure a dished diaphragm 9 to the hub 1. The diaphragm 5 is provided with lightening holes 10; the diaphragm 7 is provided with lightening holes 11; while the diaphragm 9 is provided with lightening holes 12. The periphery of the diaphragm 5 is formed with a flange 13. A flange 14 is formed at the periphery of the diaphragm 7. A flange 15 is formed at the periphery of the diaphragm 9. Stream-lined sheathing 17 is riveted, or otherwise secured, to the diaphragms 5, 7, and 9, as can readily be seen by reference to Figure 1. The sheathing 17 is provided with apertures 18 through which the propeller blades 4 pass. Stream-lined wing shields 19 are secured to the sheathing 17 around each of the apertures. The structure just described is more or less permanent, that is, it need not be removed to obtain access to the variable pitch propeller mechanism of the hub, but may be considered as being the base of the spinner, if desired. The spinner cone proper is designated by the reference numeral 20 and is so shaped that it abuts against the base of the spinner smoothly. The abutting portion of the spinner cone 20 is reinforced with a peripheral flange 21 which is secured to the spinner cone 20 by means of rivets or in any other suitable manner. The dished diaphragm 9 carries a plurality of pins 28, in suitable apertures formed in the diaphragm. Each of the pins 28 is provided with a head formed with an enlargement 22 and a portion of less diameter 23. The portion 23 is of greater diameter than the apertures in the diaphragm 9, so that the enlarged portion 22 is always spaced from the face of the diaphragm. The ends of the pins 28 are threaded to receive nuts 24. Between each diaphragm and nut 1 place a spring 25 and suitable spring washers 26 and 27, as can readily be seen by reference to Figure 5.

The peripheral flange 21 of the spinner cone 20 is provided with an internally extending portion 29. A plurality of plates 30 are secured to the flange portion 29 in any suitable manner, as by welding, riveting or otherwise. The plates 30 and the flange portion 29 are formed with keyhole slots 13, as can readily be seen by reference to Figure 2. The width of the narrow portion of the slots is equal to the diameter of the portion 23 of the head of the pin 28. The enlarged portions of the keyhole slots are of such size that the large portion 22 of the locking pin head may pass

therethrough. The sides of the slots 32 are tapered to match the tapered portion 33 of the locking pin head which joins the enlarged portion 22 with the reduced portion 23 of the locking pin head. The flange 9 also carries a locking lug 34, which can readily be seen by reference to Figure 6. The lug 34 extends through an aperture 35 formed in the flange portion 29 of the spinner cone flange. The aperture or slot 35 is of substantially the same length as the keyhole slots. The lug 34 is threaded and adapted to receive a locking screw 37 as can readily be seen by reference to Figure 6. A spacer member 36 is secured to the peripheral flange 21 of the spinner cone.

The parts are shown in the drawings in assembled and locked position. When it is desired to remove the spinner cone, the locking screw 37 is removed. The spinner cone is then rotated in a counterclockwise direction, as viewed in Figure 2. This brings the enlarged portions 22 of the bolts 28 in alignment with the enlarged portions of the keyhole slots 31. The spinner cone may then be removed by drawing it toward the mechanic. When it is desired to replace the spinner cone, it is brought to a position where the enlarged portions of the keyhole slots are in alignment with the pins.

Due to the tapered form of the sides 32 of the keyhole slot and the spacer portion 23 of the bolt-head, the leading edge of the tapered portions of the slots will engage the tapered portions 33 of the locking pin heads. The mechanic then rotates the spinner in a clockwise direction. This cams the pin heads toward the mechanic against the action of the springs 25. When the limit of motion is reached in the clockwise direction, the locking lug 34 will have its threaded aperture in alignment with the opening through the spinner cone. The locking screw 37 may be then screwed into the locking lug 34 and the assembly locked against rotation. It is to be noted that, due to the frictional engagement between the securing pin heads and the plates 39, that the spinner cone will be held in position by friction. The arrangement is such, further, that the propeller rotation will tend to move the securing pins to their securing position in the keyhole slots. Even without the locking screw 37, the spinner cone will remain in position during flight. The locking pin, however, precludes any rotational movement to unlocking position.

It will be seen that I have accomplished the objects of my invention. I have provided a spinner for variable pitch propellers which will stream-line and protect the variable pitch propeller hub. The arrangement is such that the spinner may be quickly and expeditiously removed when it is desired to gain access to the variable pitch propeller mechanism or the propeller hub, for any reason. The construction is light in weight and easy of operation.

It will be understood that certain features and sub-combinations are of utility and may be employed without reference to other features and sub-combinations. This is contemplated by and is within the source of my claims. It is further obvious that various changes may be made in details within the scope of my claims without departing from the spirit of my invention.

Having thus described my invention, I claim:

1. An aircraft propeller including in combination a hub, a spinner streamlining said hub, said spinner comprising a portion stationary with said hub and a removable nose portion, said stationary

portion being formed with openings for the passage of propeller blades, means for supporting said stationary portion from said hub, and means for supporting said removable nose portion from said hub in abutting streamlined relation with the stationary portion, said last means comprising interengaging pins and slots, mountings reciprocally supporting the pins, and springs urging the pins into said stationary portion, said pins and slots having cam surfaces for moving the pins in a nose holding position.

2. An aircraft propeller including in combination a hub, a spinner streamlining said hub, said spinner comprising a portion stationary with said hub and a removable nose portion, said stationary portion being formed with openings for the passage of propeller blades, means for supporting said stationary portion from said hub, a diaphragm supported from said hub, said removable nose portion being formed with an inwardly directed flange having cam surfaces, and readily releasable catch means, mountings reciprocally supporting the catch means, and springs urging the catch means into the stationary portion, the catch means being movable onto said cam surfaces and into frictional engagement therewith for securing said flange to said diaphragm.

3. An aircraft propeller including in combination a hub, a spinner streamlining said hub, said spinner comprising a portion stationary with said hub and a removable nose portion, said stationary portion being formed with openings for the passage of propeller blades, means for supporting said stationary portion from said hub, a diaphragm supported from said hub, said removable nose portion being formed with an inwardly directed flange, key-hole slots in the flange, pins slidably carried by the diaphragm, springs urging the pins into the stationary portion, the pins being interengageable with the slots for readily releasably securing said nose portion to the diaphragm upon relative rotation of said nose portion to said diaphragm, said slots having cam surfaces for moving the pins against the action of the springs into engaging position upon such rotation of the nose portion.

4. An aircraft propeller including in combination a hub, a spinner streamlining said hub, said spinner comprising a portion stationary with said hub and a removable nose portion, said stationary portion being formed with openings for the passage of propeller blades, means for supporting said stationary portion from said hub, a diaphragm supported from said hub, said removable nose portion being formed with an inwardly directed flange, key-hole slots in the flange, pins slidably carried by the diaphragm, springs urging the pins into the stationary portion, the pins being interengageable with the slots for readily releasably securing said nose portion to the diaphragm upon relative rotation of said nose portion to said diaphragm, said slots having cam surfaces for moving the pins against the action of the springs into engaging position upon such rotation of the nose portion and means for preventing relative rotation between said stationary portion and said nose portion when said nose portion is secured to said diaphragm.

5. An aircraft propeller including in combination a hub, a spinner streamlining said hub, said spinner comprising a portion stationary with said hub and a removable nose portion, said stationary portion being formed with openings for the

passage of propeller blades, means for supporting said stationary portion from said hub, a diaphragm supported from said hub, said removable nose portion being formed with an inwardly directed flange, pins slidably positioned in said diaphragm, said flange being formed with key-hole slots, said pins being formed with heads adapted to pass through the larger portions of said slots and to engage the metal bounding the smaller portions of said slots, and springs for urging said pins to engaging position. 10

6. An aircraft propeller including in combination a hub, a spinner streamlining said hub, said spinner comprising a portion stationary with said hub and a removable nose portion, said 15 stationary portion being formed with openings

for the passage of propeller blades, means for supporting said stationary portion from said hub, a diaphragm supported from said hub, said removable nose portion being formed with an inwardly directed flange, pins slidably positioned in said diaphragm, said flange being formed with key-hole slots, said pins being formed with heads adapted to pass through the larger portions of said slots and to engage the metal bounding the smaller portions of said slots, springs for urging said pins to engaging position, and means for preventing relative rotation between said stationary portion and said nose portion when said nose portion is secured to said diaphragm. 5

EDWARD B. BENSON.
